UNITED STATES PATENT OFFICE

LOUIS J. SAUER, OF OAK PARK, ILLINOIS, ASSIGNOR TO CHARLES H. JOY, SR., OF CHICAGO, ILLINOIS

AUTOMATIC FEEDING DEVICE

Application filed March 1, 1930. Serial No. 432,442.

My invention relates to automatic feeding devices for duplicating machines with especial reference to that class of machines provided with a flat gelatinized printing surface over which a carriage having a suitable platen roller is arranged to travel.

My invention is particularly adapted for use in connection with machines similar to that shown and described in my co-pending application, Serial No. 349,876, in which the paper or suitable cards are inserted in the carriage and the platen roller impresses the original or the copy sheet on the gelatinized printing surface which receives the impression from the original sheet and transfers it to the copy sheet.

In positioning the original or copy sheets on the gelatinized surface, it is necessary that the paper be accurately aligned with relation to the platen roller and the printing surface, and that the sheets be fed to the surface and under the platen roller in such a manner that a suitable margin will result. It is also desirable that suitable adjustable means be provided to vary the width of the margin within reasonable limits.

In my invention I have provided a convenient means for accomplishing the desired results and it has for one of its objects the provision of an automatically controlled paper stop bar and paper feeding device, the operation of which is automatically controlled relative to the directional movement of the carriage and carriage handle.

Another object is the provision of an automatic paper feeding device controlled by the operator through the normal lost motion movement of the carriage handle.

A further object is the provision of means automatically controlling a suitable paper guide to guide the paper into printing position on the printing bed during the printing movement of the carriage, and to automatically guide the paper from the printing bed during the reverse movement.

Another object is to provide a completely automatic margin controlling paper feed, and a suitable paper stop and paper guide cooperating therewith, all incorporated in the carriage of a duplicating machine and auto-

matically operable by the single means operating the carriage.

A further object is to provide an adjustable means for varying the width of the margin.

Another object is the provision of suitable means for releasing the feeding means upon movement of the carriage.

It is also an object to provide means whereby the paper feed mechanism is operated before the movement of the carriage.

A further object is the provision of means operable with the carriage for moistening the gelatinized surface of the printing bed.

Another object is the provision of an automatic feeding device controlled by the same directional movement of the handle controlling the carriage.

Further objects will appear from the detailed description to follow and from the appended claims.

In the drawings:

Figure 1 is a side elevation of the carriage and cooperating parts of a duplicating machine embodying my invention, portions being broken away to better illustrate the construction;

Fig. 2 is a perspective view of a portion of the carriage supporting bar and one of the carriage stops;

Fig. 3 is a top plan view of the carriage;

Fig. 4 is a detail sectional view, taken on a line corresponding substantially to the line 4—4 of Fig. 3 and illustrating the platen supporting latch, and platen raising means;

Fig. 5 is a sectional view through the carriage and taken on a line substantially corresponding to line 5—5 of Fig. 3, the platen roller being removed;

Fig. 6 is a detail sectional view of the platen bearing, taken on line 6—6 of Fig. 3;

Fig. 7 is a detail sectional view, taken on a line corresponding to line 7—7 of Fig. 1 and illustrates the driving means and the bearing for the paper feed roller;

Fig. 8 is a transverse sectional view through the moistening device and taken on a line corresponding to line 8—8 of Fig. 3;

Fig. 9 is a detail elevation of the operating mechanism for the feed roller and paper stop;

Fig. 10 is a detail sectional view taken on the line 10—10 of Fig. 1 and illustrates the construction of the carriage supporting rollers;

5 Fig. 11 is a diagrammatic sectional view through the platen and feed rollers and illustrates the method of feeding the paper under the platen roller to obtain a desired margin;

10 Fig. 12 illustrates a modified form of the paper feeding device.

Referring now to the drawings in detail, the embodiment shown comprises side frame members 1, on which is supported a printing bed 2, having a gelatinized, printing surface 3 (Fig. 5). The gelatinized surface usually comprises a band or ribbon which is wound on spools mounted at each end of the machine. The spools are not shown as they form no part of the present invention.

20 The band is stretched over the printing bed and may be wound from one spool to the other to provide a new and unused printing surface.

A carriage supporting bracket 5 is mounted for longitudinal movement on a guide bar 6, by means of grooved rollers 7 and 8, the rollers 7 resting on the top of the bar 6 and the roller 8 being below the bar. The bar 6 is secured to the side frame 1 in longitudinal relation to the printing bed, and is a close working fit in the roller grooves 9 (Fig. 10). This arrangement prevents lateral movement of the bracket and allows free longitudinal movement. The carriage in the present device is hinged on the bracket 5 and comprises a rectangular frame including sheet metal side bars 10 and 11, which are secured together by a front end plate 12 and a rear end plate 13. The carriage is hinged 40 to the bracket 5 by means of outwardly extending lugs 14 and 15 which are in alignment with similar inturned lugs 16 and 17, respectively, on the bracket, and are hinged thereto by means of the hollow bushings 18 secured by the nuts 19. A removable platen roller 20 is longitudinally mounted in the carriage and adjacent the printing surface. One end of the platen roller shaft 21 is rotatably mounted in a ball bearing 22, the latter being supported in a movable plate 23 which is pivoted at 24 to the carriage end plate 12.

The movable plate 23 is provided with an arm 25 normally resting on the rotatable shaft 26, which shaft is longitudinally mounted for oscillation in the carriage end plates and which is provided with a pin 27 engaging the pin 28 on the movable plate 23. The plate 23 is normally held in the position shown in Fig. 5 by a spring 29. It will be clear, from the drawings, that if the shaft 26 is rotated in a clockwise direction the bearing will be raised to raise the platen roller from the printing surface.

60 The opposite end of the platen roller is sup-

ported in a slot 30 in a movable bearing plate 31, pivoted at 32 on the carriage end plate 13. The latch 33 is pivoted on the plate at 34 and arranged to engage the roller shaft 21 and support it in the bearing slot 30. The bearing plate 31 is similar to the opposite bearing plate 23 and is also provided with an arm 35 resting on the shaft 26 and normally held in that position by a spring 36. A pin 37 on the shaft 26, engages a pin 38 on the plate 31, the latter being raised when the shaft 26 is rotated. By this arrangement of bearing plates and operating mechanism both of the bearings are raised simultaneously when the shaft 26 is rotated. The shaft 70 may be rotated to raise the platen roller at any time, by means of a finger lever 39 pivoted at 40 on the carriage handle lever 41 on which latter is mounted a suitable handle 42. The handle lever is pivoted on a rod 43, which also acts as a guide for a slotted link 44 connected to the finger lever 39. A pin 45 on the link engages a pin 46 on the shaft 26. The handle lever is pivoted for lost motion relative to the carriage, for reasons to be later described, and it is obvious that the finger lever 39 and cooperating platen raising mechanism may be effectively operated, with the handle in any lost motion position. It will also be clear that with the construction just described the platen roller is free to adjust itself to any inequalities in the printing surface.

75 The ball bearing 22 comprises a stub shaft 47 mounted in bushings 48 and 49 which are in turn secured to the movable plate 23. The slot 50 in the end plate 12 allows free movement of the bearing. A drive pulley 51 is secured to the stub shaft by a screw 52. A tongue portion 53, on the platen roller shaft 100 is removably engaged in a slot 54 in the stub shaft.

100 A roller 55 on the carriage end plate 13 engages the side frame 1 and supports the carriage thereon, and when the carriage is raised the platen roller may be easily removed by releasing the latch 33 from engagement with the shaft 21. The latch is normally held in engaged position by a spring 56.

105 The driving spool or pulley 51 is rotated in the usual manner by means of a single turn of a cable 53, the cable being secured to the side frames 1 (Fig. 1). The lower edge of the platen driving roller 51 is always in alignment with the axial line of the hinges and the cable 53 extends through the hollow bushings 18. By this construction the cable is always in alignment with the bushings, even when the carriage is raised. A paper table 56 is mounted on the carriage side bar 11 at a suitable angle and arranged to guide the paper under the platen roller, where it will be pressed against the gelatinized surface of the printing bed and receive the impression. As previously mentioned, the car-

riage handle is pivoted for a lost motion movement, so that when the carriage is moved toward the left, as viewed in Fig. 1, the handle takes the position shown in full lines, 5 and when it is moved to the right, takes a position substantially as shown by dotted lines, thus giving a lost motion of the handle for each directional movement of the carriage. In order that the paper may be fed 10 under the platen roller from the paper table in such a manner that a suitable margin will be obtained, I provide a suitable paper stop and paper feeding device which comprises a feed roller 57 mounted in suitable bearings 15 in the carriage end plates and extending adjacent to and in alignment with the lower edge of the paper table 56. The feed roller is preferably rubber covered. A shaft 58 is oscillatably mounted above the paper table 20 and in suitable bearings in the end plates and provided with arms 59 rigidly secured thereto and supporting a rotatably mounted pressure roller 60 in longitudinal relation to the feed roller. 25 A spring 60a tends to normally press the roller 60 against the feed roller 57, and it will be noted that by oscillating the shaft 58 the pressure roller 60 will be pressed against or raised away from the feed roller 57. A 30 paper stop bar 61, preferably of sheet metal, is loosely mounted on the shaft 58 and provided with a depending portion 62 for engaging and retaining the paper on the paper table when the feed and pressure rollers are 35 separated. When the carriage handle 42 is in the full line position shown in Figs. 1 and 5, the feed and pressure rollers will be separated, as shown, to allow the paper to be inserted and rest against the depending portion 40 of the paper stop. The pressure roller is raised and held in the raised position by a pin 63 on the shaft, which is engaged by a lug 64 on a slidable plate 65, the plate 65 being guided and supported on the end plate 45 12 by means of a pin 67 in a slot 68, the lower part of the plate resting on an inwardly extending guide portion 69 of the end plate. The slidable plate 65 is held in the position indicated in Figs. 1 and 5 by means of a pawl 50 link 70, which is pivoted at 71, on the handle lever, and which is provided with an upwardly extending latch portion 72 engaging in a notch 73 in the plate 65.

It will be obvious from the relative positions of the parts as shown in Figs. 1 and 9 55 that when the handle is pushed forward the plate 65 will also be moved and the lug 64 will release the pin 63 on the shaft 58, allowing the spring 60a (Fig. 4) to rotate the shaft 60 and engage the paper between the pressure 65 and feed rollers. At the same time, the cam surface 75 on the plate 65, which surface is engaged by the outwardly extending lug 76 on the paper stop bar 61, will cause the stop bar to be raised to the position shown in Fig.

9 to allow the feed roller to feed the paper beneath the platen roller.

During the lost motion movement of the handle the feed roller is operated by means of a rack 78 which is guided in the angularly disposed slot in the end plate 12. The rack is arranged to engage a pinion 79 on the gear 80, which is mounted on the end plate 12 and which in turn engages the pinion shaft 81 of the feed roller and which is mounted in the bearing 82 (Fig. 7), the bearing being cut away at 83 to provide suitable clearance for the gear. The rack is provided with a pin 84 engaging in a slot 85 in the pawl link 70, thus providing a lost motion between the pawl link and the rack. When the handle is moved forward the plate 65 will only be moved a distance sufficient to release the pressure roller and raise the paper stop bar as previously described. The upwardly extending latch portion 72 of the pawl link will simultaneously be released from the notch 73, the release being accomplished by the downward angular movement of the pawl link, caused by the lost motion of the rack pin 84 in the angular slot 85. The plate will then remain stationary while the handle is moved forward until a pin 86, which is secured to the handle lever and extends through the slot 87 in the end plate, engages an adjustable stop member 88 having steps 88a. During this continued movement the feed rollers will be operated to feed the paper to the platen roller.

The stop member 88 is made adjustable by means of a screw 89 in slot 90, and is for the purpose of limiting the lost motion movement of the handle, and thereby limiting the distance that the paper will be fed toward the platen roller. When the adjustable stop is in its lowermost position the steps 91 will not be engaged by the pin 86 and the complete movement of the handle will be utilized to feed the paper to provide the widest obtainable margin. As the adjustable stop is raised 100 the various steps will be engaged by the pin 86 and the paper will be fed a distance corresponding to the step engaged.

Fig. 11 illustrates the position of the platen roller, relative to the front edge of the printing surface, when the feed roller is operated. When the carriage is at the extreme end of the forward movement, the platen roller will be slightly beyond the front edge of the printing surface leaving an opening through which the paper will feed to provide the desired margin corresponding to the lost motion of the handle. The paper will be engaged immediately upon the forward movement of the carriage.

The feed roller is of such diameter that the adjustment of the stop to provide the shortest lost motion of the handle will allow the feed roller to revolve sufficiently to provide the least margin and further adjustment of

the stop will allow the paper to be fed a greater distance to provide a greater margin.

In order to release the paper from the feed roller so that it may be engaged by the platen roller when the carriage starts its forward movement, I provide an arm 92 secured to a rod 93, which latter is pivotally mounted in the carriage end plates. A roller 94 on the lever rests on the side frame 1, the front portion of which is cut away at 95. As soon as the handle has reached the forward position to move the carriage, the roller 94 will be raised by the shoulder 96 on the side frame and the upwardly extending arm 97 of the lever will engage the pressure roller supporting arm 59, and the pressure roller will be raised and the paper released.

As previously described, the platen roller may be raised with the carriage at any position over the printing surface by this means, and by operating the handle through its lost motion, paper may be fed under the platen roller to any desired position on the printing surface.

In order to guide the paper under the platen roller a curved paper guide 98 is pivoted on the frame end plates at 99 and extends parallel with the roller. This paper guide is connected to the movable plate 65 by a link 100 so that when the device is in the paper feeding position, the guide will be lowered to the dotted line position, shown in Fig. 9, to guide the paper under the platen roller, and when the handle is in the position shown in Fig. 5 and the feed rollers are separated, during the return movement of the carriage, the paper guide will be raised to the position shown in Fig. 5 and the paper will be removed from the printing bed and guided to an easily accessible position between the margin bar and the platen roller where it may be removed from the machine.

Carriage stops 101 are adjustably mounted on the carriage guide bar 6 and are secured in adjusted position by the thumbscrews 102. These stops cooperate with rubber bumpers 103 secured to the bracket 5, and limit the movement of the carriage to correspond to the length of the paper used.

It is desirable, at times, to moisten the printing surface with each movement of the carriage. For this purpose I provide a tank 104 (Fig. 8) for containing water or other suitable fluid, a wick 105 extends through the wall of the tank and contacts with a felt covered roller 106 which is pivoted to suitable arms 107, the latter being secured to the shaft 108 mounted in suitable bearings on the carriage. By this means moisture may be supplied to the surface as desired. When moisture is not needed the roller may be left in the raised position shown by dotted lines.

In the modified form shown in Fig. 12 the handle lever 41 is pivoted at 109, and the feeding is accomplished by the downwardly ex-

tending feeding member 110 pivoted at 111 on the lever 112, which latter is pivoted to the handle and pressed downwardly by the spring 113. The feeding member 110 is normally held in feeding position by the spring 114 and is raised at each end of the lost motion movement of the handle by the cams 115 and 116 engaging the pin 117. The feeding member 110 is preferably rubber covered as shown to provide a better gripping surface.

In operation, with the carriage in its extreme forward position, paper may be inserted to rest against the paper stop and the handle will be moved to push the carriage rearwardly. During the lost motion of the handle and before the carriage starts, the pressure roller will be lowered to grip the paper between the rollers, the paper stop will be raised, the paper guide will be lowered, and the paper will be fed under the platen roller. The carriage will then start its forward movement and the pressure roller will simultaneously be raised to release the paper and allow it to be pressured against the printing surface by the platen roller.

Upon the return movement of the handle the lug 72 on the pawl link 70 will again engage in the slot 73 to return the plate 65 to its original position, and the paper guide will raise to remove the paper, the paper stop will simultaneously be lowered, and the carriage moved to the original forward position, from which the operations may be repeated.

Having thus described my invention, what I claim and desire to secure by Letters Patent is:

1. A duplicator comprising a bed having a printing surface, a carriage bracket arranged for longitudinal movement relative to said bed, a carriage hinged to said bracket for movement therewith and for pivotal movement relative thereto, a platen roller on said carriage, and a driving means for said roller extending thru and substantially on the axial line of said hinge.

2. In a duplicating machine, a carriage mounted to travel over a printing bed and having a platen roller cooperative with said bed, a handle for operating the carriage and having a lost motion relative thereto, a margin controlling paper-feeding means, and an adjustable means for limiting the lost motion to vary the margin.

3. In a duplicating machine, a carriage mounted to travel over a printing bed and supporting a platen roller cooperative with said bed, a handle for operating said carriage and having a lost motion relative thereto, a margin controlling paper-feeding means, and an adjustable means for limiting said lost motion to control the paper-feeding means.

4. In a duplicating machine, a carriage mounted to travel over a printing bed and having a platen roller cooperative with said

- bed, a handle for operating said carriage and having a lost motion relative thereto, and a paper-feeding means completely operable by the lost motion movement of the handle.
5. In a duplicating machine, a carriage mounted to travel over a printing bed and having a platen roller cooperative therewith, a handle for operating said carriage and having a lost motion relative thereto in the direction of carriage travel, and a margin controlling paper-feeding means completely operable by the lost motion movement of said handle, and means for limiting the lost motion to vary the margin.
6. In a duplicating machine, a carriage mounted to travel over a printing bed and having a platen roller cooperative therewith, means for operating said carriage, means for feeding paper under said platen roller, and transmission means between said carriage operating means and said feeding means for operating said feeding means independent of said carriage.
- 25 7. In a duplicating machine, a carriage mounted to travel over a printing bed and having a platen roller cooperative therewith, means for operating said carriage, means for feeding paper under said platen roller, transmission means between said carriage operating means and said feeding means for operating said feeding means independent of said carriage travel, and means for raising said platen roller to allow the paper to be fed thereunder.
8. In a duplicating machine, a carriage mounted to travel over a printing bed and having a platen roller cooperative therewith, a paper table, a movable paper stop-means, a paper feeding means, a movable paper guide means for guiding the paper to and from said platen roller, and a single carriage operating handle for operating all of said means previous to the operation of the carriage.
- 45 9. In a duplicating machine, a carriage mounted to travel over a printing bed and having a platen roller cooperative therewith, a paper table, a movable paper stop, a paper feeding means, a single means for operating said paper stop and said paper feeding means, and means for limiting the paper feeding operation independent of the paper stop.
- 55 10. In a duplicating machine, a carriage mounted to travel over a printing bed and having a platen roller cooperative therewith, a paper table, a movable paper stop, a paper feeding means comprising a feed roller and a pressure roller, said paper stop and said pressure roller being simultaneously operable to alternately engage the paper, a carriage operating means and means cooperating with said carriage operating means to operate all of said paper controlling means.
- 60 11. In a duplicating machine, a carriage mounted to travel over a printing bed, a paper table on said carriage, a paper feeding means comprising a movable paper stop and a pressure roller, a carriage operating means, means cooperating with said carriage operating means for simultaneously operating said paper stop and said pressure roller to alternately engage the paper, and means independent of said last named operating means for releasing said pressure roller upon movement of said carriage.
12. In a duplicating machine, a carriage mounted to travel over a printing bed, a paper table on said carriage, a paper feeding means comprising a movable paper stop and a pressure roller, a carriage operating handle having a lost motion in the direction of the carriage movement, means cooperating with said handle for operating the feeding means during the lost motion movement of said handle, and means for freeing the paper from the feeding means during the movement of the carriage.
13. In a duplicating machine, a printing bed having a gelatinized surface, a carriage mounted to travel over said surface, means on said carriage for moistening said surface comprising a container for fluid, a fluid-distributing roller engaging said surface, a wick for delivering fluid from said container to said roller, and means for removing said roller from engagement with said surface.
14. A duplicating machine comprising a printing surface, a guide extending along the side of said printing surface, a bracket mounted for longitudinal movement on said guide and non-rotatable with respect thereto, a carriage pivotally mounted on said bracket to swing toward and from the printing surface about an axis substantially parallel to said guide, a platen roller mounted on said carriage for applying paper to the printing surface, a drum for driving said platen roller, and a flexible member passing around said drum for driving it, the axis about which the carriage swings being substantially tangential to the periphery of the drum.
15. A duplicating machine comprising a printing surface, a guide extending along the side of said printing surface, a bracket mounted for longitudinal movement on said guide and non-rotatable with respect thereto, a carriage pivotally mounted on said bracket to swing toward and from the printing surface about an axis substantially parallel to said guide, a platen roller mounted on said carriage for applying paper to the printing surface, a drum for driving said platen roller, and a flexible member passing around said drum for driving it, the ends of said flexible member being secured at points lying substantially in the axis about which the carriage swings.
16. A duplicating machine comprising a printing surface, a guide extending along the

side of said printing surface, a bracket mounted for longitudinal movement on said guide and non-rotatable with respect thereto, a carriage pivotally mounted on said bracket to swing toward and from the printing surface about an axis substantially parallel to said guide, a platen roller mounted on said carriage for applying paper to the printing surface, a drum for driving said platen roller, and a flexible member passing around said drum for driving it, the axis about which the carriage swings being substantially tangential to the periphery of the drum, and the ends of said flexible member being secured at points lying substantially in said axis.

In witness whereof, I have hereunto subscribed my name.

CERTIFICATE OF CORRECTION.

Patent No. 1,817,103.

Granted August 4, 1931, to

LOUIS J. SAUER.

It is hereby certified that error appears in the printed specification of the above numbered patent requiring correction as follows: Page 5, line 24, claim 6, after "carriage" and before the period insert the word travel; and that the said Letters Patent should be read with this correction therein that the same may conform to the record of the case in the Patent Office.

Signed and sealed this 22nd day of September, A. D. 1931.

(Seal)

**M. J. Moore,
Acting Commissioner of Patents.**
